DESIGN FOR A NIPPLE FOR NURSING BOTTLES

Brij Orath Theodore Bery, London, England

Application November 28, 1944, Serial No. 116,596
In Great Britain June 5, 1944

Term of patent 7 years

(Cl. D83—1)

To all whom it may concern:

Be it known that I, Brij Orath Theodore Bery, a British subject and a resident of London, England, have invented a new, original, and ornamental Design for a Nipple for Nursing Bottles, of which the following is a specification, reference being had to the accompanying drawing, forming part thereof.

Referring to the drawing,

I claim:

The ornamental design for a nipple for nursing bottles, substantially as shown.

BRIJ ORATH THEORORE BERY.
